UNITED STATES PATENT OFFICE.

ERNST BOESSNECK, OF CHEMNITZ, GERMANY, ASSIGNOR TO CHARLES HENRY ALDRIDGE, OF LOUGHBOROUGH, ENGLAND.

KNITTING-MACHINE.

SPECIFICATION forming part of Letters Patent No. 658,826, dated October 2, 1900.

Application filed May 29, 1900. Serial No. 18,352. (No model.)

To all whom it may concern:

Be it known that I, ERNST BOESSNECK, a subject of the German Emperor, residing at Chemnitz, Saxony, in the German Empire, have invented certain new and useful Improvements in Rotary or Flat Bar Knitting-Machines, of which the following is a specification.

This invention consists of certain improvements in rotary or flat bar knitting-machines, and is particularly applicable to the type known as "Cotton's," where such are used or adapted for making lace or open work hose, socks, underwear, and the like. In these machines I use fixed lacing-points carried by bars or fingers fast to a suitable rod carried by the ordinary narrowing-machine and receiving the necessary endwise movements from special mechanism for the transfer of loops from needle to needle.

The main object of my invention is to enable fully-fashioned hose, socks, underwear, and the like to be made by the operation of fixed lace-points and with the lacework or open-work running within a few needles of each selvage all through the fashionings, and also to enable the lacework to be carried down the heels and instep, while at the same time the selvages of both the heels and insteps or other partings may be properly formed.

To enable the lace work to be carried within a few stitches or needles of each selvage whatever the width of the fabric, notwithstanding that the fixed lacing-points may cover the full width of the fabric that can be made upon the machine, I cause flat fingers to act upon the heads of certain predetermined needles and hold them forward in such a manner that the lacing-points cannot remove the loops from those needles, so that wherever these flat fingers are situated when in action there plain fabric will be formed, and in order to enable the fabric to be fashioned at the same time I arrange the fashioning-points behind the lacing-points, and when a fashioning is required the lacing-points are turned up out of the way and the whole of the narrowing-machine is brought forward, whereby the fashioning-points come into acting position. All these movements I produce

automatically in a manner and by means hereinafter described.

In order to produce the necessary predetermined variable transferring movements of the lacing-points, I arrange a pattern-wheel provided with one, two, or more concentric rows of studs of varying heights, which can be shifted and arranged in any desired order of height. These studs are caused to come into contact with a stud or projection upon a special slide in consecutive order, and the varying heights of the said studs determine the position of the said slide. To this slide the lacing-point bar is attached, so that the varying heights of the said studs determine the needles or make the selection of needles from which loops are to be taken. The said special slide has a cross-slide combined with it in such a manner that the movement of the cross-slide in one direction causes the loops removed (according to the selection made by the studs of varying height) to be transferred to the right and the movement of the cross-slide in the opposite direction causes the loops removed to be transferred to the left. All these arrangements are controlled from the pattern-wheel by rows of studs acting upon suitably-arranged levers, all worked and arranged as hereinafter described; and in order that "drop-stitch" work may be produced I arrange and apply special sliding trucks or rollers to the narrowing-machine lifting-arms, which are brought into or out of the path of special cams. When these special cams come into action, the loops, after being removed from the needles, are not transferred to adjacent needles, but are dropped off, and a "ladder" or run is formed back to the last locked loop. All these several variable movements of the several parts of the machine may be automatically controlled by studs set and arranged upon one or more chains, which are fully described hereinafter.

The several improvements will be understood by referring to the accompanying drawings, where the mechanism relating thereto, together with some adjacent parts, is shown.

In the drawings I have only shown so much of a knitting-machine as is directly affected by my invention, the other parts not shown

being similar to those used upon or in ordinary plain knitting-machines of the Cotton type, which is well understood by all conversant with knitting-machines—such, for example, as shown in the specification of Cotton's British Patent, No. 3,123, of 1864.

Figure 1, Sheet 1, is a part section through the narrowing-machine and same adjacent parts. Fig. 2, Sheet 2, is a part front view of the same. Fig. 2^A, Sheet 2, is a part plan of part of same. Fig. 3, Sheet 3, shows a part section through another part of the narrowing-machine. Fig. 4 is a part front view of same, and Fig. 5 is a part plan of two of the rods of same and some adjacent parts. Fig. 6, Sheet 4, is a part front view with some parts in section, showing the general arrangement of the pattern-wheel, the racking-tackle, and some adjacent parts. Fig. 6^A is a detail view of the upper end of the rocking clawker or ratchet which acts upon the rack-wheel that is fast to the ordinary narrowing-screw. This form of pawl or clawker is the same as that shown in Aldridge's United States Patent No. 614,599. Fig. 7, Sheet 5, is a part end view of parts of same. Fig. 8, Sheet 6, is a part plan of the several racking-levers at left-hand end of the machine. Fig. 8^A is an elevation of the fashioning racking-lever T, shown in plan in Fig. 8. Fig. 9, Sheet 7, is a plan of part of Fig. 6, Sheet 4. Fig. 10, Sheet 7, is an enlarged elevation and part section of the special slide and cross-slide that works in conjunction with the studs on the pattern-wheel. Fig. 11, Sheet 8, is a part plan of Fig. 10. Fig. 12, Sheet 9, is an enlarged part elevation of the inner face of the pattern-wheel, indicating the position of the studs thereon and the slide upon which they act, also showing the studs upon the peripherical face. Fig. 13, Sheet 9, shows an enlarged view of a needle, a lacing-point, a fashioning-point, and a stopping-finger in their approximate relative position at the time the remainder of the lacing-points (not opposite the stopping-fingers) are removing loops from their respective needles. Fig. 14, Sheet 9, shows the points and needles in their approximate relative position when the narrowing-machine is moved forward, the lacing-points lifted, and the fashioning-points in the position for removing loops from the needles. Fig. 15, Sheet 10, is a front elevation showing the chief parts of the mechanism for shogging the cam-shaft, also the chain and the mechanism directly connected therewith by which all the various sections of mechanism are automatically controlled. Fig. 16, Sheet 11, is a part plan of Fig. 15, Sheet 10. Fig. 17, Sheet 12, is a part section of part of Fig. 15, Sheet 10. Fig. 18, Sheet 13, is another part sectional elevation of parts of Figs. 15 and 16. Fig. 19 is a full size plan of a portion of the controlling-chain, showing the position of studs; and Fig. 19^A is a side elevation of same. Fig. 20, Sheet 14, is a diagrammatic sketch plan of the outline of a machine, showing the general

disposition of the several truck-arms or levers, hereinafter described.

In all the several drawings in order to avoid confusion I have purposely left out parts of other views which are not essential to make the particular part described understood.

A, Fig. 1, designates the needles, A' the sinkers, and A² the knocking over bits.

B is the narrowing-machine shaft, which is carried in or by special bearings, hereinafter described. The position of this shaft in the machine is shown in Fig. 7.

B' are the narrowing-machine arms, which are fast to the shaft B. These arms carry the shaft B², to which the brackets B³ are fast. These brackets carry the sliding rods B⁴ B⁵, to which the fashioning-fingers B⁶ and B⁷ are attached, the finger B⁶ being fast to the rod B⁴ and the finger B⁷ to the rod B⁵.

B⁸ are the coverers or fashioning-points.

The finger B⁶ transfers the loops at the left-hand selvage, and the finger B⁷ transfers the loops at the right-hand selvage in the usual well-understood manner.

The necessary rising and falling movements are imparted to the narrowing mechanism by means of cams and levers through the connecting-link B⁹ in the usual well-understood manner.

C represents the lacing-points carried by the bar or brackets C', which is fast upon the lace-point rod or bar C². The bar or bracket C' may be as wide as the full width of the division of needles or fabric and the lacing-points C may be arranged at any distance apart in the bar C' to suit the pattern desired to be produced. The rod C² (and consequently the fingers C', fast thereto) receives the necessary endwise movement for the transfer of loops to form the lace-work by means hereinafter described, and it is capable of being so turned or rocked in its bearings, by means also hereinafter described, that the points C may be turned into the position indicated by dotted lines in Fig. 1 and full lines in Fig. 14, Sheet 9.

A bracket C³ is fast to the shaft B² and so adjusted as to form a support for the lace-point bar C' when the points are in their working position.

It will be seen that the coverer or fashioning-points B⁸ are situated behind the lacing-points C. When the lacing-points C are in action, they are in the position shown in full lines in Fig. 1, and when they descend to shift loops from the needles the coverer-points B⁸ pass between the knocking-over bits, but do not come into contact with the needles; but when a fashioning is desired the points C are turned up out of action, as indicated by dotted lines, and the fashioning-points B⁸ are brought into acting position by means hereinafter described. I will first describe in detail the pattern-wheel and mechanism connected therewith used for controlling the endwise movements of the lace-point rod C² to effect the necessary transfer of loops from needle to

needle. Figs. 6 to 12, Sheets 4 to 9, show this arrangement and some adjacent parts.

D is the pattern-wheel, which is carried by the fixed pin or axle D'. This wheel is provided with a convenient number of teeth D². To give a step-by-step rotating movement to this wheel, an arm or lever D³ (see Fig. 7) is carried by a pin or axle D⁴. This arm is provided with a truck or roller D⁵, which is acted upon by the cam D⁶, which is fast to the cam-shaft X. To the end of the lever D³ a ratchet D⁷ is suitably jointed, and this ratchet acts upon the teeth D² on the wheel D, so that by the action of the cam D⁶ the wheel D is caused to rotate step by step as desired.

Upon the inner face of the wheel D, I arrange two or more rows of pegs, studs, or stops of various heights or lengths, (see Figs. 10, 11, and 12,) which may be arranged in any order of length desired. A few of these studs are shown at D⁸ and D⁹, Fig. 12, Sheet 9. Also two only of these studs are shown in Figs. 10 and 11, Sheets 7 and 8; but it will be understood that these studs are continued all around the wheel, the outer row of studs being marked D⁸ and the inner row D⁹. A slide E, Figs. 10 and 11, Sheets 7 and 8, which I will call the "main" slide, is fitted and free to slide lengthwise in a bed or bracket E'. This bracket is suitably fixed to the framing of the machine. Fast to the slide E is a bracket E², suitably connected to the end of the lace-point rod C² by any convenient attachment, such as the two collars C⁴ C⁴, as shown. Thus any endwise movement imparted to the main slide E is also imparted to the lace-point rod C², while still allowing the lace-point rod to be raised and lowered. Another slide (which I will call the "secondary" slide) E³ is free to slide endwise in the main slide E, which is best seen in Fig. 10, Sheet 7. This slide is provided with a suitable cross bolt or slide E⁴, Figs. 10, 11, and 12, the lower end of which is provided with a stud or pin E⁵, which engages with either the row of studs D⁸ or D⁹, according to the position of the bolt E⁴ as regulated by the attendant. A bracket E⁶ is fast to the main slide E, and its base may form a cover or cap for the secondary slide E³, as shown. This bracket E⁶ carries a vertical slide or bolt E⁷, which passes through the main slide E and through a suitable hole in the bed E', but does not come into contact therewith. The face of this slide E⁷ nearest to the end E¹¹ of the secondary slide E³ is so cut or shaped that it has three steps or faces E⁸, E⁹, and E¹⁰, each step or face being the distance of one needle—i. e., the distance from center to center of two adjacent needles—above or below the adjacent step or face. The end E¹¹ of the secondary slide E³ is held in contact with one or other of these steps or faces by a suitably-located spring, such as shown at E¹², Figs. 10 and 11. Now it will be seen that if an endwise movement be imparted to the cross slide or bolt E⁷, so as to bring one or other of the steps

E⁸, E⁹, or E¹⁰ into contact with the end E¹¹ of the secondary slide E³, the extreme ends of the main and secondary slides will be caused to advance or retire the one from the other, according to which of the said steps are brought into action. The whole compound slide E, E³, and E⁷, together with the lace-point rod C² and its attachment, is held or drawn toward the pattern-wheel D by the spring E¹³, Fig. 11, Sheet 8. The said compound slide is drawn away from the pattern-wheel and the bolt E⁷ is moved up and down by means hereinafter described. The relative movements of the pattern-wheel D and the compound slide above described I will now explain.

The pattern-wheel D is racked around step by step by the ratchet D⁷, as hereinbefore described. In the drawings I have indicated two rows of studs D⁸ and D⁹ on the side face of the pattern-wheel D, and the bolt E⁴, I have shown in its lowest position, so that the stud or screw E⁵, carried thereby, is in the position to engage with the row of studs D⁹. The studs D⁸ and D⁹ are of various heights and are arranged in a regular predetermined order, according to the pattern desired. The compound slide is drawn away from the pattern-wheel D by means hereinafter described and while so drawn back the wheel is racked forward one or two teeth, as also hereinafter described. The compound slide is then allowed to be drawn back by the spring E¹³, so that the stud E⁵ on the bolt E⁴ engages with a stud D⁹ on the wheel D. During these movements the bolt E⁷ is in the position shown in Fig. 10—i. e., with the face or step E⁹ in contact with the end E¹¹ of the secondary slide E³. The lace-points C are then in position for taking loops off certain needles, according to the arrangement or order of the points C in the bracket C' and according to the height of the stud D⁹ then in action. The loops being removed from their respective needles are then transferred to the adjacent needles right or left, as follows: If the loops are required to be shifted to the right, the bolt or slide E⁷ is raised (by means hereinafter described) so that the step or face E⁸ comes into contact with the end E¹¹ of the slide E³. It will be seen that this movement of the bolt E⁷ will move the main slide E (and consequently the lace-point rod C² also) one needle to the right, and the loops are thus transferred to the right, as desired. If the loops are required to be shifted to the left, the bolt or slide E⁷ is lowered, so that the face or step E¹⁰ comes into contact with the end E¹¹ of the slide E³ and the main slide E, together with the lace-point rod C² and all attached thereto, will be drawn to the left a space of one needle by the action of the springs E¹² and E¹³, and the loops are thus transferred to the left, as desired. Thus it will be seen that the varying heights of the studs D⁸ or D⁹ upon the side face of the pattern-wheel D control or select the needles from which

loops are taken, and the rising or falling movement of the cross slide or bolt E⁷ controls the direction right or left in which the loops are transferred. The two or more rows of studs 5 D⁸ D⁹ on the side face of the pattern-wheel D are so arranged that each row represents a distinct pattern—as, for instance, in making lace socks, hose, and the like—where a heading or bracelet is first made, followed by 10 a repeating pattern for down the leg and foot. In such a case the row of studs D⁸ might be used when forming the bracelet, the bolt E⁴ being lifted, so as to bring the stud E⁵ into the path of the row of studs D⁸. Then when 15 the bracelet is completed the bolt E⁴ is lowered, so that the stud E⁵ comes into the path of the studs D⁹, which are arranged for the repeating pattern, or vice versa.

The compound slide may be automatically 20 drawn away from the pattern-wheel D while the said wheel is racked (as hereinbefore described) as follows: An arm F, Figs. 6, 7, and 8, Sheets 4, 5, and 6, one end of which is carried by a fixed pin or axle F', which may be 25 fast to any convenient part of the machine. This arm F carries a truck or roller F², Figs. 6 and 8, which runs upon a suitable cam F³, Fig. 6. From this cam the lever F receives a suitable rising-and-falling movement. A 30 connecting-rod F⁴ joins the end of the lever F to the end F⁵ of the bell-crank lever F⁵ F⁶, which works upon the fixed axle F⁷. The top end F⁶ of the said bell-crank lever engages with the bracket E¹⁴, Figs. 6, 9, 10, and 11, 35 which is fast to the main slide E. Thus by the movement imparted by the cam F³ the whole compound slide is moved to the right while the pattern-wheel is racked forward.

The cross slide or bolt E⁷ may be automatically 40 raised or lowered (as and for the purpose hereinbefore described) as follows: An arm or lever G, Figs. 6, 7, and 8, one end of which works upon the fixed axle D¹, has a truck or roller G', which is acted upon by the three-step cam G² G³ G⁴, Fig. 6. Another arm or lever G⁵, one end of which is carried by a pin or axle in the fixed bracket G⁶, Figs. 6, 7, and 9, is connected to the arm G by a suitable connecting-rod G⁷. The bottom end E¹⁵, Figs. 7 45 and 10, Sheets 5 and 7, of the bolt E⁷ rests upon the front end G⁸ of the lever G⁵ and is kept in contact therewith by the spring E¹⁶, Figs. 6 and 10. When the truck G' is on the cylindrical surface G⁴, the bolt or slide E⁷ will 50 be in the position shown in Fig. 10—i. e., with the face or step E⁹ in contact with the end E¹¹ of the secondary slide E³. When the said truck is on the cam G², the step or face E⁸ of the bolt or slide E⁷ will, when the cams as 55 they revolve come into the position shown in Fig. 7, be brought into action, and the loops will be then transferred to the right, as hereinbefore described, and when the said truck is on the cam G³ the step or face E¹⁰ comes 60 into action, and the loops are then transferred to the left, as also hereinbefore described.

It will be understood by all conversant with

this class of machinery that when a lace course or fashioning course is made the cam-shaft X is shogged to the right a distance equal to 70 the thickness of the cams, and by this movement the set of fashioning-cams are brought into action. In Fig. 6 the shaft X is shown in its shogged position. When the cam-shaft X is in its normal position—i. e., when the frame is making the plain courses—the truck G' runs upon the cylindrical surface G⁴. Then when the cam-shaft X is shogged the cams G² or G³ come into action according to the position of the truck G' upon its pin or axle. 75 This truck G' has two positions upon its pin or axle, the one position shown by full lines and the other by dotted lines in Fig. 8. When it is in the position shown in full lines, the cam G² comes into action in the lacing 80 course, and when in the position indicated by dotted lines the cam G³ comes into action, and the truck is shifted from one position to the other automatically as follows: A forked lever H, Fig. 8, is centered upon a pin or axle 85 H', fast to the racking-arm G. The forked end of the lever H embraces the truck G', and the other end is acted upon by the spring H² and tends to hold the truck G' in the position shown by full lines in Fig. 8.

A lever H⁵, Figs. 6 and 7, Sheets 4 and 5, is jointed at one end on the pin or stud H⁶, (see Fig. 7,) and from the other end of this lever H⁵ a rod H⁷ is suspended. The lower end of this rod H⁷ is provided with an incline 90 or wedge-shaped surface H⁸, one side of which slides in a suitable guide on the lever G, and the other side of this incline H⁸ engages with the projection H⁹, Fig. 8, on the lever H. These parts are so adjusted that when the lever H⁵ is lifted (by means yet to be described) the incline or wedge-shaped end H⁸ of the rod H⁷ acts upon the projection H⁹ on the lever H, and thereby shifts the truck G' into the position indicated by dotted lines in Fig. 8.

Round the peripheral surface of the pattern-wheel two rows of studs, such as H³ H⁴, Figs. 10, 11, and 12, may be arranged to lift the lever H⁵, whereby the truck G' is shogged or shifted on its axle, as hereinbefore described, according to the predetermined order and arrangement of the studs H³ and H⁴. Either the row of studs H³ or the row H⁴ are caused to act upon the lever H⁵ by means yet to be described, the row H³ being brought into action synchronously with the row of studs D⁸ on the side face of the pattern-wheel D and the row H⁴ with the row D⁹, or vice versa.

Two suitably-shaped fingers or inclines are jointed to the middle, or thereabout, of the lever H⁵, having their acting ends H¹⁰ H¹¹, Fig. 6, so shaped and adjusted that the rows of studs H³ H⁴ may act thereon. The other ends of these fingers may be formed into handles H¹² H¹³, by which either finger may be turned 120 into or out of action, as desired. In Figs. 6 and 7, H¹⁰ is shown out of action and H¹¹ in action. Now it will be seen that by means of the handles H¹² H¹³ either of the rows of studs

$H^3 H^4$ may be brought into action, as desired, and as the row of studs D^8 or D^9 in the side face of the pattern-wheel select the needles from which loops are to be taken so likewise 5 the row of studs H^3 or H^4 on the peripherical face of the pattern-wheel determine the direction in which the loops are transferred.

In some cases it is desirable that the pattern-wheel should be racked forward two teeth 10 at one movement at certain parts of its revolutions in order that its cycle of movements may be completed in a less number of movements than the number of teeth in the wheel in order to accommodate varying lengths of 15 patterns desired. This I effect as follows: A special row of studs J , Figs. 10 and 11, are arranged upon the peripherical face of the pattern-wheel D . These studs act upon the nose of the lever J' , Fig. 7, Sheet 5. This 20 lever is jointed upon the fixed pin or axle H^6 . From the back end J^2 of the lever J' a connecting-rod J^3 descends to the bell-crank lever J^4 , (see Fig. 7,) which is carried by the fixed pin or axle J^5 . The lower end J^6 of the bell- 25 crank lever J^4 is shaped as shown. The back end of the lever D^8 is suitably shaped so that it may rest upon the end J^6 of the bell-crank lever J^4 . Now it will be seen that when a stud J comes under the end of the lever J' 30 the end J^6 of the bell-crank lever J^4 will be brought into the position indicated by dotted lines in Fig. 7, and will then be clear of the racking-lever D^8 . The action of these several parts are as follows: The cam D^6 , Fig. 35 6, Sheet 4, is so shaped that when in full action the ratchet D^7 , worked thereby, will rack the pattern-wheel D two teeth at each movement. Now when there is no stud under the end of the lever J' the bell-crank lever J^4 40 supports the end of the racking-lever D^8 in such a position that it does not receive the full action of the cam D^6 , but only sufficient thereof to rack the pattern-wheel D one tooth at each movement. Thus it will be seen that 45 when there is no stud J under the nose of the lever J' the pattern-wheel is racked one tooth at a time, and when a stud J comes into action it is racked two teeth at a time as and when desired, according to the arrangement 50 of the studs J .

I will now describe the arrangement by which the lacing-points or the fashioning-points are brought into action.

It will be seen, as hereinbefore described, 55 that the fashioning-points are behind the lacing-points when the latter are in action, (see Fig. 1, Sheet 1,) and the fashioning-points are therefore out of contact with the needles. When a fashioning is desired, I cause the lacing-points to move into the position indicated by dotted lines in Fig. 1 and full lines in Fig. 14, Sheet 9, by means hereinafter described, and I cause the whole narrowing-machine to move forward a small space by means yet to be described, so that the fashioning-points B^8 60 come into acting position with the needles A . Instead of the narrowing-machine back shaft

B , Fig. 1, being carried in fixed bearings, as is usually the case, I carry the said shaft in movable bearings formed in the top ends of 70 links, such as B^{10} , Fig. 1. The bottom ends of these links B^{10} may work upon the shaft B^{11} (known as the "catch-bar" shaft) or other convenient part. A bar B^{12} , Figs. 1 and 2^A, 75 may rest in suitable brackets or bearings. This bar is provided with wedge-shaped or inclined surfaces B^{13} , which engage with the projections B^{14} . A spring or springs B^{15} (see Fig. 1) may be attached to the links B^{10} and to any convenient part of the framing or 80 brackets attached thereto, which tend to hold the narrowing-machine back in its normal position; as seen in Fig. 1. Now it will be seen that if the bar B^{12} be moved in the direction of the arrow B^{16} , Fig. 2^A, the incline B^{13} , acting upon the projection B^{14} , will cause the 85 whole narrowing-machine to move forward a distance equal to the lift of the incline B^{13} , which is just sufficient to bring the fashioning-points B^8 into acting position, and when 90 the bar B^{12} is moved back again into its normal position, as shown in Fig. 2^A, the pull of the springs B^{15} and the natural weight of the narrowing-machine will cause the narrowing-machine to fall back into its normal position— 95 *i. e.*, correct for the lace-points C to come into action—as shown in Figs. 1 and 13, Sheets 1 and 9. The bar B^{12} may be moved automatically by means hereinafter described. It will be evident that instead of the shaft B being carried by the links B^{10} it may be carried 100 in sliding bearings or the equivalent; but I prefer to use the links, as shown.

When using a lace-point bar C' , as hereinbefore described, having fixed points C for the 105 full width, or nearly so, of the division of work or needles and the work is fashioned or narrowed, it will be readily seen that unless prevented by special means the lace-points would sometimes act right on the selvage and so 110 cause a bad ragged selvage. This I arrange for as follows: Two rods K and K' , Fig. 1, Sheet 1, may be carried by the same brackets as the fashioning-finger rods $B^4 B^5$ and the lace-point rod C^3 or by independent brackets. 115 A suitably-shaped finger or bracket K^2 , Figs. 1 and 2, is fast to the rod K , and a similar bracket K^3 is fast to the rod K' . These brackets I will call the "stopping-fingers." The rod K is connected to the left-hand fashioning-finger rod B^4 and the rod K' to the right-hand fashioning-finger rod B^5 by means hereinafter described. The stopping-fingers $K^2 K^3$ are so set upon their respective rods that 120 they cover a certain predetermined number of needles at each selvage, and the rods $K K'$, being connected to their respective finger-rods, always maintain their respective position to the selvage-needles in whatever position the fashioning-fingers may be racked into 125 during the process of fashioning. These stopping-fingers $K^2 K^3$ are so shaped and located 130 and have such a rocking movement imparted to them (by means hereinafter described) that

at the moment when the lace-points are taking their loops from the needles the stopping-fingers $K^2 K^3$ engage with the heads of the needles over which they move and hold those 5 needles slightly forward, as shown in Fig. 13, Sheet 9, so as to prevent the lace-points from taking loops from those needles. Thus it will be seen that these stopping-fingers $K^2 K^3$ insure that no lace-work shall be made within 10 a certain predetermined distance from each selvage whatever the width of the fabric being made.

In some cases—as, for instance, when making heels and insteps—at the same time it 15 is desirable that after the lace-work has been formed for a certain distance down the heel the lacing should cease all across the heel-pieces and continue down the instep only. To do this, I construct the stopping-fingers $K^2 K^3$ of a width sufficient to cover 20 the width of the heel-pieces and then so arrange the connections of the rods $K K'$ to the rods $B^4 B^5$ that the stopping-fingers $K^2 K^3$ may be set to cover a few needles at each selvage or the entire width of the heel, as desired.

In some cases it is desirable that a strip of plain fabric should be left down some part of the lace-work—as, for instance, when making longitudinal partings in the middle of a piece of work and two or more plain selvages are desired in addition to the outer selvages of the fabric. To do this, I employ another rod L , situated above the rods $K K'$ or in 35 other convenient position. This rod L may carry suitable stopping-fingers $L' L^2$, Fig. 2, similar in construction and working to the stopping-fingers $K^2 K^3$, above described. These fingers $L' L^2$ may receive the necessary 40 movement, as hereinafter described, and may be set at any part of the fabric where the plain strips are desired.

I will now describe the rocking movement and connections for the rods $C^2, K, K',$ and L . 45 An arm C^6 , Fig. 3, Sheet 3, may be fast to the rod C^2 at any convenient part of its length, and a lever $C^6 C^7$ may rock upon the shaft B^3 , the end C^6 being connected to the arm C^5 by means of the rod C^8 . To the end C^7 a connecting-rod C^9 is attached. This rod C^9 is attached at its lower end to a suitable truck-lever C^{10} , Fig. 20, Sheet 14, through which the necessary rocking movements are imparted to the lace-points to lift or turn them 55 into the position indicated by dotted lines in Fig. 1 and full lines in Fig. 14, Sheet 9, when a fashioning is made, as hereinbefore described.

It has been hereinbefore explained that when the lacing-points are in action the bar 60 C' , Fig. 1, Sheet 1, to which they are attached, rests against the supporting bracket C^3 . Now in order that the bar C' may be kept against the bracket C^3 more or less independently of the action of the cams operating the rod C^2 65 through the connecting-rod C^9 , I attach several arms, such as C^{12} , to the rod C^2 , each of these arms carrying a truck or roller C^{13} . In

front of these I arrange suitably-shaped brackets C^{14} , which may be fast to any convenient part of the framing of the machine. 70 When the narrowing-machine descends and the lace-points come into action, the trucks C^{13} engage with or run upon the inner faces of the brackets C^{14} , which are so shaped and adjusted that they just keep the lace-point bars C' against their respective supporting-brackets C^3 . Then when a fashioning is made and the lace-points are turned up out of action, as hereinbefore described, the trucks C^{13} are thereby turned up also, and therefore 80 do not come into contact with the brackets C^{14} .

Two arms $K^4 K^4$, Figs. 1 and 2, may be fast to the rod K at any convenient part of its length. (See Fig. 2.) These two arms may carry a rod or bar K^5 . To the end or other 85 convenient part of this rod a connecting-rod K^6 may be attached, and the top end of this connecting-rod may be attached to the end K^7 of the lever $K^7 K^8$, Fig. 1, which is free to rock on the shaft B^2 . The end K^8 of the lever K^7 is connected by a rod K^9 to a truck-lever K^{11} , Fig. 20, Sheet 14, through which the necessary rocking movements may be imparted to the rod K . An arm K^{10} is fast to the rod K' . The end of this arm K^{10} is held 95 in contact with the rod or bar K^5 by a suitable spring. (Not shown.) It will be seen that by these means any rocking movement imparted to the stopping-finger rod K through the connecting-rod K^9 is also imparted to the second stopping-finger rod K' . In a precisely-similar manner an arm L^3 may be fast to the rod L and held in contact with the rod K^5 by a suitable spring. (Not shown.) Thus it will be seen that through the one connecting-rod K^9 the three rods $K K' L$, and consequently the stopping-fingers $K^2, K^3, L',$ and L^2 , also receive the necessary rocking motions.

The fashioning-finger rods $B^4 B^5$ may be 110 connected to their relative stopping-finger rods $K K'$ as follows: An arm M , Figs. 3, 4, and 5, Sheet 3, may be fast to the finger-rod B^4 . The other end of the arm M may be forked, as at M' , Fig. 5, and embrace freely 115 the stopping-finger rod K . A collar M^2 (provided with a suitable "wing" or "thumb" screw or other convenient fastening) also embraces the rod K and fits between the fork M' of the arm M . Two other collars $M^3 M^4$ 120 may be fast to the rod K to act as stops for the rod K against the fork M' of the arm M . It will be remembered that in some cases it is desirable that the stopping-fingers $K^2 K^3$ should be shifted sidewise, so as to stop off 125 only a few needles at each selvage or right across the heel-pieces, as hereinbefore described. Now it will be seen that by slackening the thumb-screw in the collar M^2 the rod K may be shifted sidewise, so that the collar M^3 is against the fork M' , as shown in Fig. 4, or the collar M^4 may be brought against the fork M' , as shown in Fig. 5, and the collars $M^3 M^4$ may be set to any distance apart 130

desired. The collars M^3 M^4 thus serve as stops to allow the rod K being quickly moved endwise either into a position for the stopping-fingers to stop off only a few needles at each selvage or to stop off any larger number of needles that may be desired. The rod K' may be similarly attached to rod B^3 , as indicated in Fig. 4. By these means both the stopping-fingers K^2 K^3 may be shifted at will, so as to make plain work at the selvages only or right across the heels, as desired.

In some cases when making lace-work it is desirable to make "drop-stitch" work at the same time or independently. In either case the drop-stitch may be made as follows: Loops are picked off certain needles and transferred to adjacent needles. Then after a given number of plain courses loops are again removed from the same needles; but instead of being transferred the lace-points are lifted and the loops thereon dropped off. Thus a "ladder" or "run" is formed back to the transferred loops first removed. To do this, the first loop is transferred, as for lace-work, by the action of the pattern-wheel and adjacent parts, as hereinbefore described. The second loop is likewise picked off, but instead of being placed upon an adjacent needle, as when lacing, special extra narrowing-machine-lifting trucks or rollers are automatically shifted upon their axles, as hereinafter described, so that they run upon special cams, which are so shaped as to lift the narrowing-machine, and consequently the lace-points also, sufficiently high to drop the loops off the lace-points without transferring them. Thus drop-strokes are formed when and where desired, and ladders or runs of any length are formed as desired. This arrangement will be understood by referring to Figs. 15, 16, and 17, Sheets 10, 11, and 12. N , Fig. 16, is an ordinary narrowing-machine-lifting arm, the end N' being jointed upon the shaft N^2 . (See Figs. 15 and 16.) The front end N^3 carries an axle N^4 , to which the lifter B^4 , Fig. 1, is attached. N^5 is the truck or roller which runs upon the collar N^6 and cam N^7 , Fig. 15, the collar N^6 being in action during the plain course and the cam N^7 being in action during the fashioning or lacing course. Another truck N^8 is free to slide upon the boss of the truck N^5 in such a manner by means hereinafter described that it can either occupy the position shown in the drawings or be moved close up to the face of the truck N^5 . A special cam-segment N^9 , Fig. 15, may be fast to the side of the cam N^7 just at the part which is in action when the lace-points are replacing their loop upon the needles. Now it will be seen that when the cam-shaft X is shogged to the right when a lace course is made and the cam N^7 comes under the truck N^5 the truck N^8 will miss the cam-segment N^9 , while the said truck N^8 remains in the position shown; but if the said truck be shifted up to the face of the truck N^5 then the cam-segment N^9 will act upon the truck N^8 , and

the narrowing-machine will be lifted, so that the lace-points drop their loops, as hereinbefore described. A forked lever N^{10} , (see Fig. 16,) jointed upon a fixed pin or axle N^{11} , which is fast to the arm N , may enter a groove in the boss of the truck N^8 . The back end N^{12} of this lever may be suitably connected to the rod N^{13} by the collars N^{14} N^{14} or other convenient means, so that by shifting the rod N^{13} endwise the truck N^8 and other similar trucks upon the other narrowing-machine-lifting arms along the machine may be brought into and out of action, as desired. 70 75 80

I will now describe how the several parts hereinbefore described may be automatically controlled from one pattern-chain.

Figs. 15 to 18, Sheets 10 to 13, show the ordinary well-understood general arrangements 85 of the cam-shaft-shogging tackle, together with some adjacent parts. O^1 are the shogging-cams on the cam-shaft X . O^2 is the shogging-arm carrying the truck O^3 , (see Fig. 15,) which is acted upon by the said shogging-cams O^1 in the usual well-understood manner. O^4 is another truck attached to the arm O^2 and acted upon by the cam O^5 , Figs. 15 and 18. This cam lifts or rocks the arm O^2 , so that the truck O^3 is shifted or moved from 90 the path of the cam O to the path of the cam O' . The arm O^2 is fast to the shaft O^6 , and also fast to this shaft is the arm O^7 , which acts upon the tooth-wheel O^8 . This wheel is fast to the ratchet-wheel O^9 . A pawl O^{10} acts 95 upon the ratchet-wheel O^9 . The said pawl O^{10} is carried by the arm O^{11} and receives the necessary motion from a cam O^{12} . (See Fig. 16.) When the wheel O^8 is racked around, the nose of the arm O^7 rests either on the top 100 of a tooth or in a space. When on the top of a tooth, the cam O' is in action, and the cam-shaft X is shogged to the right, and when in a space the cam O is in action and the cam-shaft X is shogged to the left—that is, back 105 into its normal position. All this is well understood by all conversant with this class of knitting machinery.

P, Figs. 15 to 17, is a chain-wheel, around which an endless chain P' passes. This chain-wheel is racked around step by step in the usual well-understood manner by means of the lever P^2 , Fig. 17, and the pawl P^3 , Fig. 15, carried by it, which acts upon the rack-wheel P^4 , Fig. 15, which is fast to the chain-wheel P . The chain P' (a few bars of which are shown in Figs. 19 and 19^A, Sheet 13) may be provided with two rows of studs, such as P^5 P^6 , and extra broad studs P^7 , or a third row of studs, as most convenient. A lever 115 P^8 , Figs. 15 and 16, is jointed upon or carried by the fixed stud P^9 . This lever is acted upon by the row of studs P^6 or P^7 . The other end of this lever P^{10} is connected by the rod P^{12} , Fig. 15, to the pawl O^{10} , these several parts 120 being so adjusted that when a stud P^6 or P^7 comes under the nose of the lever P^8 the pawl O^{10} comes into action, the tooth-wheel O^8 is racked, and the cam-shaft X is shogged 125 130

for narrowing or lacing, as hereinbefore described, and when there is no stud below the nose of the lever P^8 the spring P^{13} , acting upon the end P^{10} of the lever P^8 , holds the pawl O^{10} out of action. This will be well understood by all conversant with this class of machinery. Thus it will be seen that the row of studs $P^6 P^7$ regulate the lacing and fashioning courses. A second stud-lever R , Fig. 16, may be carried by the fixed stud or axle P^9 and may be acted upon by the row of studs P^5 . This lever has a vertical arm or member R' . (See Fig. 15.) A lever R^2 , Figs. 15, 16, and 17, may be jointed upon the fixed axle R^3 . It carries a truck R^4 , (see Figs. 16 and 17,) which works upon the cam R^5 or the run or disk R^6 . The back end R^7 of the lever R^2 is connected by the rod R^8 to the bell-crank lever $R^9 R^{10}$, Fig. 15. The said lever $R^9 R^{10}$ may be carried by an axle fixed to any convenient part of the machine. The end R^{10} of the bell-crank lever $R^9 R^{10}$ may be connected to the rod R^{12} by the collars $R^{11} R^{11}$ or other convenient means. The arm or member R' of the stud-lever R is so arranged that when there is no stud P^5 under the nose of the lever R it supports the end of the lever R^2 , Fig. 17, and the truck R^4 is prevented from following the path of the cam R^5 when the cam-shaft X is shogged for a lace or fashioning course, as hereinbefore described; but when a stud P^5 comes into action the prop R' is moved into the position indicated by dotted lines in Fig. 15. The truck R^4 follows the path of the cam R^5 , whereby the rod R^{12} is shifted in the direction of the arrow R^{13} , Fig. 15. This rod R^{12} may run from end to end of the machine and be supported by suitable brackets fast to convenient parts of the framing of the machine. This rod R^{12} shifts all the several trucks hereinbefore described that have to be shifted into a second position when a fashioning is made, so that when a fashioning is required a stud P^5 is placed upon the chain P , and the necessary changes from the plain or lacing course to the fashioning courses are automatically effected.

To cause the narrowing-machine to be shifted bodily forward, as hereinbefore described, when a narrowing is to be made, a lever S , Figs. 15, 16, and 18, Sheets 10, 11, and 13, may be carried by a fixed pin or axle S' and carries a truck S^2 , which works upon the run or disk S^3 on the cam S^4 . The other end S^5 of the lever S is connected by the rod S^6 to the end S^7 of the bell-crank lever $S^7 S^8$, which may be carried by a fixed pin or axle attached to any convenient part of the framing of the machine. The top end S^8 of the said bell-crank lever is connected in any convenient manner to the rod B^{12} , hereinbefore described. Thus it will be seen that the action of the cam S^4 moves or draws the rod B^{12} in the direction of the arrow B^{16} , (see Fig. 2^A, Sheet 2,) and so causes the narrowing-machine to shift bodily forward. The rod B^{12} may be drawn in the reverse direction to the arrow B^{16} by a

suitable spring B^{17} when the narrowing-machine is to be allowed to move back to its normal position. A forked lever S^9 , Figs. 16 and 18, suitably jointed to the arm S , embraces the truck S^2 . A forked arm S^{11} , fast to the rod R^{12} , embraces the end S^{10} of the lever S^9 , so that when the rod R^{12} is moved in the direction of the arrow R^{13} , as hereinbefore described, the truck S^2 is brought into the path of the cam S^4 , when the cam-shaft X is shogged, as hereinbefore described. Fig. 20, Sheet 14, is a diagrammatic sketch plan showing the general disposition of the several trucks acted upon by the said rod R^{12} .

The ordinary well-understood racking-levers T are shown at the extreme ends of Fig. 20, and a more detailed view of one lever is shown in Figs. 6, 8, and 8^A, Sheets 4 and 6. The lever T works upon the axle D^4 , Fig. 8, and carries a truck T' , which is acted upon by the cam T^2 , Fig. 6. T^3 is the racking-clawer or ratchet which acts upon the rack-wheel T^4 , Figs. 6 and 9, which is fast to the ordinary narrowing-screw T^5 , Figs. 6 and 9, Sheets 4 and 7. A forked lever T^6 , carried by a suitable bracket from the arm or lever T , may embrace the truck T' . (See Fig. 8, Sheet 6.) The other end T^7 of the forked lever T^6 may be embraced by the forked bracket T^8 , Figs. 5 and 8, Sheets 4 and 6, which is fast to the rod R^{12} , so that when the rod R^{12} is moved to the right when a fashioning is required, as hereinbefore described, the truck T' is brought into the path of the cam T^2 , when the cam-shaft X is shogged, and the screw T^5 (and consequently the stops and other parts attached thereto) is racked as desired. The truck of the racking-lever T at the other end (see Fig. 20, Sheet 14) is shifted in a precisely-similar manner by the rod R^{12} .

When a fashioning is made, it is necessary that the truck D^5 , carried by the pattern-wheel-racking lever D^3 , should be moved from the path of the cam D^6 in order that the pattern-wheel may not be then rocked. This is effected as follows: A lever D^{10} , Fig. 8, Sheet 6, may be jointed to a pin or axle D^{11} , which may be fast to a convenient part of the racking-lever D^3 . A pin or equivalent may be fast to the lever D^{10} , so as to engage with and work in a suitable groove in the pipe or boss of the truck D^5 . The other end D^{12} of the lever D^{10} is embraced by the forked bracket D^{13} , also fast to the rod R^{12} . Thus it will be seen that when the rod R^{12} is moved to the right, as hereinbefore described, the truck D^5 is moved out of the path of the cam D^6 and the pattern-wheel is not racked.

I will now describe how the rod N^{13} , Figs. 15, 16, and 17, Sheets 10, 11, and 12, is worked from the hereinbefore described chain P' and causes the lace-points to drop all loops which they have taken from the needles.

A stud arm or lever V , Figs. 15 and 16, carried by a shaft V' , is acted upon by the wide stud P^7 , Fig. 19, Sheet 13. The shaft V' may be carried by suitable brackets or bearings

and passed through to the back of the machine. To the back end of the shaft V' an arm V^2 may be attached, and from the end of this arm V^2 a connecting-rod V^3 passes upwards to an arm V^4 . (Seen best in Fig. 15, Sheet 10.) This arm V^4 may be jointed to a boss or bracket V^5 , which is fast to the rod N^{18} . Another lever V^6 may be jointed upon a stud or pin V^7 , which may be carried by a suitable fixed bracket V^8 , Fig. 17, Sheet 12. The end of the lever V^6 is held against the collar V^9 (which is fast to the cam-shaft X) by a suitable spring V^{10} . (See Fig. 16.) It will now be seen that when the cam-shaft is shogged to the right the end V^{11} , Fig. 16, Sheet 11, of the lever V^6 will be moved to the left. The end of the hereinbefore-described arm V^4 , (see Fig. 15,) which is jointed to the rod N^{18} and connected to and lifted by the stud-lever V , is so arranged and adjusted that when in its raised position—*i. e.*, when a stud P^7 comes under the nose of the stud-lever V —it engages with the end V^{11} of the lever V^6 , and when there is no stud under the nose of the lever V it just misses the end V^{11} of the lever V^6 . Thus it will be seen that when a stud, such as P^7 , lifts the nose of the lever V the end V^{11} of the lever V^6 catches the end of the arm V^4 , so that when the cam-shaft X shogs to the right the rod N^{18} is moved to the left and the special truck or trucks N^8 on the narrowing-machine lifting-arms N are brought into action, as and for the purpose hereinbefore described.

The truck-arm K^{11} , Fig. 20, Sheet 14, which imparts the necessary rocking movements to the hereinbefore-described fingers $K^2 K^3$, which serve to hold some of the needles away from the lacing-points, is also provided with a shogging-truck K^{12} , which is worked or shifted by the movement of the rod R^{12} precisely as hereinbefore described in relation to the lever S and the truck S^2 , Figs. 16 and 18, Sheets 11 and 13. In a similar manner the truck-arm C^{10} has a shogging-truck C^{11} , which is likewise shifted by the movement of the rod R^{12} , and this truck-arm C^{10} is connected to the connecting-rod C^9 , Fig. 3, Sheet 3, through which the necessary rocking movements are communicated to the lace-points C . Thus it will be seen that the one chain P' may control all the necessary movements of the several parts or sections of mechanism brought into operation during the lacing or fashioning courses, as hereinbefore described, so that when a stud P^6 comes under the nose of the stud-lever P^8 the cam-shaft X is shogged to the right, bringing into action all the cams necessary for controlling and producing the necessary movements of the needles and other working parts, together with the special mechanism for controlling the lace-points and all connected therewith, all hereinbefore described in detail. Then when a fashioning is desired a stud, such as P^5 , is inserted in the chain P' . This stud causes the rod R^{12} to be shifted to the right, as hereinbefore described,

by which means the trucks T' on the racking-levers T are brought into action. The truck D^5 on the pattern-wheel-racking lever D^8 is thrown out of action. The truck K^{12} on the truck-lever K^{11} is passed onto a special cam, whereby the stopping-fingers $K^2 K^3$ are lifted into the position indicated by dotted lines in Fig. 1, Sheet 1. The truck S^2 on the truck-lever S is brought into action, whereby the narrowing-machine is brought forward bodily. The truck C^{11} on the truck-lever C^{10} is shifted onto a special cam, whereby the lacing-points are lifted into the position indicated by dotted lines in Fig. 1, all as hereinbefore described. Then when a drop-stitch course is required a wide stud, such as P^7 , is inserted in the chain and the stud-lever V is lifted, causing the rod N^{18} to be moved to the left, whereby the special trucks N^8 are brought into the path of the special cams N^9 , Figs. 15 and 16, Sheets 10 and 11, and the loops are dropped off. Thus the one chain P' may control all the operations necessary for lacing and fashioning, all the said operations having been severally and particularly hereinbefore described.

It will be evident that where desired two or more chains may be used for independently controlling the several parts or sections of mechanism, instead of all being controlled from one chain, as hereinbefore described.

What I claim is—

1. In a rotary or flat-bar knitting-machine for making "lace" or open-work by the action of lacing-points all fixed on a lace-point rod the combination consisting of the needles the rod-carrying lacing-points at any desired distance apart mechanism for lowering and raising the rod to cause the lace-points to take loops from such needles as they are then opposite to, a slide parallel with the rod to which one end of the rod is so coupled that the rod must move endwise with the slide, a pattern-wheel having projecting from its side face studs or pegs of varying heights ranged in a concentric circle or circles, a spring drawing the slide endwise and normally holding the slide against one or other of the studs, means for from time to time moving the slide away from the face of the pattern-wheel and means for simultaneously turning the pattern-wheel a distance to move one stud out of position for serving as a stop for the slide to be held against and bringing another stud into its place.

2. The combination of mechanism for shifting the lace-point bar a distance endwise after the lace-points have taken loops from some of the needles to bring the lace-points into position to deliver the loops to adjacent needles right or left as required such combination consisting of the lace-point bar, the slide to which it is coupled, a second slide movable endwise along the first, a third slide movable crosswise of the others in guides upon the first slide, steps formed on one face of the cross-slide, a spring acting on the second slide to hold it against one or other of these steps,

a pattern wheel or surface, a spring to draw the first slide endwise in a direction to hold the second slide against the pattern-surface and means for shifting the cross-slide endwise so that one step upon it may be shifted out of position for the second slide to rest against and another step brought into position and the bar so shifted to the right or left.

3. The combination of the pattern-wheel, mechanism for giving a step-by-step turning movement to this wheel, a row or rows of studs on one side face of this wheel, a lace-point bar carrying lacing-points at any desired distance apart, mechanism acted on by these studs for controlling the endwise position of the bar at the time when the lacing-points are taking loops from some of the needles, a row or rows of studs around the periphery of the pattern-wheel, and mechanism acted on by these studs for shifting the lace-point bar a distance to the right or left after the lacing-points have taken loops from some of the needles.

4. The combination of the pattern-wheel, mechanism for giving a step-by-step turning movement to this wheel, a concentric row or rows of studs on one side face of this wheel, the lace-point bar carrying lacing-points at any desired distance apart, the slide to which it is coupled, a second slide movable endwise along the first, a third slide movable crosswise of the others in guides upon the first, steps formed on one face of the cross-slide, a spring acting on the second slide to hold it against one or other of these steps, a spring acting on the first slide to hold the second slide which it carries against one or other of the studs on the side face of the pattern-wheel, a row or rows of studs around the periphery of the pattern-wheel and mechanism acted on by these studs for shifting the third or cross slide endwise and thereby causing the lace-point bar to be shifted a distance to the right or left after the lacing-points have taken loops from some of the needles.

5. The combination of the pattern-wheel, mechanism for giving a step-by-step turning movement to this wheel, two or more concentric rows of studs on one side face of this wheel, the lace-point bar carrying lacing-points at any desired distance apart, the slide to which the lace-bar is coupled, a second slide movable endwise along the first, a third slide movable crosswise of the others in guides upon the first, steps formed on one face of this cross-slide, a spring acting on the second slide to hold it against one or other of these steps, a fourth slide movable across the second slide in guides upon it and having a projection upon it which by moving the slide in its guides can be brought opposite to the studs in either of the concentric rows of studs, a spring acting on the first slide to draw it in a direction to hold this projection against one of the studs, two or more rows of studs around the periphery of the pattern-wheel, a lever

having projections upon it one for each row of studs, either one or other of which projections can be brought into position to be acted on by its row of studs and mechanism acted on by the lever for shifting the third or cross slide endwise to cause the lace-point bar to be shifted endwise to the right or left.

6. The combination of the pattern-wheel, mechanism for giving a step-by-step turning movement to this wheel, a row or rows of studs on one side face of this wheel, a lace-point bar carrying lacing-points at any desired distance apart, mechanism acted on by these studs for controlling the endwise position of the bar at the time when the lacing-points are taking loops from some of the needles, a row or rows of studs around the periphery of the pattern-wheel, and mechanism acted on by these studs for shifting the lace-point bar a distance to the right or left after the lacing-points have taken loops from some of the needles, an additional row of studs on the pattern-wheel, and mechanism acted on by these studs to control whether the pattern-wheel shall be turned one or two steps at each turning movement.

7. The combination of the lacing-points, the fashioning-points in a plane in rear of them, a rock-shaft and arms extending from it by which both sets of points are carried, movable bearings for the rock-shaft, and mechanism for shifting the bearings backward or forward to bring either the lacing-points or the fashioning-points into acting position.

8. The combination of the lace-point bar carrying lacing-points at any desired distance apart, the brackets in which it is mounted, the fashioning finger-bars mounted on the same brackets and carrying fashioning-points in a plane in rear of the lacing-points, the shaft to which the brackets are fixed, narrow-machine arms extending from a rock-shaft and carrying the first shaft, movable bearings for the rock-shaft mechanism for shifting these bearings backward or forward to bring either the lacing-points or the fashioning-points into acting position, and mechanism for turning away the lace-points whenever the fashioning-points are brought into action.

9. The combination of the lace-point bar carrying lacing-points at any desired distance apart, the brackets in which it is mounted, the fashioning finger-bars mounted on the same brackets and carrying fashioning-points in a plane in rear of the lacing-points, the shaft to which the brackets are fixed, narrow-machine arms extending from a rock-shaft and carrying the first shaft, movable bearings for the rock-shaft mechanism for shifting these bearings backward or forward to bring either the lacing-points or the fashioning-points into acting position, arms fixed to the bracket-shaft, arms fixed to the lace-point bar and fixed guide-surfaces for these arms to bear against when the points are made

to descend or ascend and cause the lace-point bar to be at these times firmly held against the arms fixed on the bracket-shaft.

10. The combination of the lace-point bar carrying lacing-points at any desired distance apart, fashioning-point bars carrying fashioning-points, flat-ended fingers carried by rods coupled to the fashioning-point bars so that they move endwise with them and which when the lacing-points descend hold the heads of any desired number of needles at each selvage away from the lacing-points so that the lacing-points cannot take loops from those needles.

15 11. The combination of the lace-point bar carrying lacing-points at any desired distance apart, fashioning-point bars carrying fashioning-points, two rods coupled to the two fashioning-rods so as to move endwise with them and carrying flat-ended fingers for holding a predetermined number of needles at each selvage away from the points when the points descend, and a third rod carrying other flat-ended fingers to hold back other needles and so cause straight strips of plain work to be formed in the work wherever desired or plain straight selvages when making "instep-partings" or the like in hose, socks or other articles.

30 12. The combination of the lace-point bar carrying lacing-points at any desired distance apart, fashioning-point bars carrying fashioning-points, two rods coupled to the two fashioning-point bars so as to move endwise with them, two flat-ended fingers each of sufficient length to act upon a large number of needles, means for readily affixing these fingers to the rods in any desired position so that at one time they may be set to act only upon a few needles at each selvage and then be set inward one toward the other so as then to cover a large number of needles and thereby allow of plain heel-pieces being formed with a laced instep-piece between them in the manufacture of socks and stockings.

45 13. The combination of the lacing-point bar, the fashioning-point bars and the rods carrying flat-ended fingers for holding back some of the needles all carried by the same 50 brackets.

14. The hereinbefore-described combination of mechanism for causing loops removed by the lacing-points to be dropped off from them whenever it is desired to form "dropped-stitch" work, such combination consisting of 55 the lace-point bar having lacing-points fixed to it at any desired distance apart mechanism for lowering raising and racking the lace-point bar to cause the lacing-points to take loops from some needles and transfer them to 60 others and automatic mechanism for giving an additional lift to the lace-point bar whenever desired to cause the loops which have been taken by the lacing-points to be slipped off from them to produce "dropped-stitch" 65 work.

15. The combination of the lace-point bar having lacing-points fixed to it at any desired distance apart, the brackets in which it is mounted, the shaft to which the brackets are 70 fixed, narrowing-machine arms extending from a rock-shaft and carrying the first shaft, a rod descending from the first shaft, a lever to which the lower end of the rod is connected, two trucks carried on the lever one acted on 75 by a cam on the cam-shaft to lower and raise the narrowing-machine to cause loops to be taken by the lacing-points from some needles and delivered to others, and automatic mechanism acting on the second truck to shift it 80 into position to be acted on by a second cam-surface on the cam-shaft to give an additional lift to the narrowing-machine whenever desired to cause the loops taken by the lacing-points to be dropped off from them and not 85 placed onto other needles.

16. In a rotary or flat-bar knitting-machine the combination of a pattern-chain, mechanism for giving a step-by-step movement to the chain, three sets of studs on the chain, mechanism 90 acted on by one set of studs for producing a fashioning course, mechanism acted on by a second set of studs for producing a lacing course and mechanism acted on by the third set of studs for producing dropped-stitch 95 work.

ERNST BOESSNECK.
